UNITED STATES PATENT OFFICE

164,476

LIQUOR POURER

George Clare, Maplewood, N. J., assignor to Claremould Plastics Corporation, Newark, N. J., a corporation

Application March 8, 1949, Serial No. 1,277

Term of patent 7 years

(Cl. D58—10)

To all whom it may concern:

Be it known that I, George Clare, a citizen of the United States of America and a resident of the city of Maplewood, in the county of Essex and State of New Jersey, have invented a new, original, and ornamental Design for a Liquor Pourer, of which the following is a specification, reference being had to the accompanying drawing, forming a part thereof:

Fig. 1 is a front view of a liquor pourer showing my new design,

Fig. 2 is a side view thereof,

Fig. 3 is a top view thereof, and

Fig. 4 is a bottom view thereof.

I claim:

The ornamental design for a liquor pourer, substantially as shown.

GEORGE CLARE.
